UNITED STATES PATENT OFFICE.

SAMUEL GARVER THOMSON, OF NEW YORK, N. Y.

HIGHWAY ATTACHMENT FOR RAILWAY CAR WHEELS.

Application filed November 22, 1923. Serial No. 676,425.

Modern transportation problems in the handling of freight and in the trucking of goods and commodities of all description have so increased, particularly at large terminals and congested distributing centers that an effort has been made to solve the same, in part at least, by the more extended use of the motor truck or motor propelled vehicle. That in turn has suggested the possible use of the motor truck or motor propelled vehicle upon either a railway track or upon the highways or streets. The present invention is concerned with adapting one and the same vehicle upon both a railway track and upon the highways or streets; and to that end contemplates a novel highway attachment for flanged railway car wheels.

While convertible wheels for use on either railway tracks or highways have heretofore been devised the same have been faulty in design and have not properly taken into consideration the peculiarities of the wear of the tread and flange of a car wheel. According to the chief object of the present invention is to provide a thoroughly practical design of highway member for application to flanged railway car wheels, which in nowise depends for its fit or support upon the portions of the car wheel which become altered by wear or by machining to restore contour. Furthermore, the invention has particularly in view, a construction admitting of quick change from a car wheel to a highway wheel and vice versa, that being an indispensable feature for a convertible wheel employed for instance, on both track and highway during the day's work in the handling and shifting of freight in large centers of population.

In general the invention contemplates a simple and economical type of highway member adapted to engage and to coat with a flanged railway car wheel and which may be readily applied and removed with facility and speed, during a single trip passing over a route involving track, platform, loading yard, street, highway, etc.

In carrying forward these objects, the invention is susceptible of a wide range of modification without departing from the spirit or sacrificing any of the advantages of the invention; but for illustrative purposes there are shown in the drawings, certain preferred and practical forms, in which:

Figure 1 is a general view illustrating a basic feature of the invention, namely, that

of a highway member engaging and mounted upon a flanged car wheel, so as to entirely clear all wearing parts of the car wheel; the view also showing by dotted lines the normal contour of a new car wheel tread and flange, and by full lines the "condemning limit" in the wear of a car wheel tread and its flange which is substantially in accordance with the requirements of the American Railway Association.

Figure 2 is a vertical cross-sectional view of a flanged car wheel showing one form of fastening means that may be employed for quickly clamping in place and quickly releasing the highway member.

Figure 2a is a plan of the locking means used in Figure 2.

Figures 3, 4 and 5 are detail views of the rim part of the car wheel engaged by different designs of highway members.

Figure 6 is a view similar to Figure 2 showing a further modification as well as a simplification of the invention.

Figure 7 is a view similar to Figure 6 showing a further modification of the invention.

Figure 8 is a sectional view of a portion of a flanged car wheel showing a modified form of highway member which is constructed with a hub-element constituting a part of the holding means for fastening the highway member to the car wheel.

Figures 9, 10 and 11 are similar sectional half-views, respectively illustrating different modifications in the hub construction of that type of highway member having a hub element for attachment to the hub part of a flanged car wheel.

Figures 12 and 13 are sectional views showing a novel form of wedge holding or clamping means that may be employed respectively with different forms of highway members.

Figures 14 and 15 are sectional half-views showing forms of highway members which take a bearing engagement on the underside of the outer rim portion of the flanged car wheel, and adapted respectively for carrying solid single and solid double cushion tires.

Figure 16 is a sectional half-view showing a form of highway member in which a bearing gusset is punched therefrom to engage with a part of the flanged car wheel not subject to wear or to machining to restore contour.

Figure 17 is a fragmentary elevation of

the form of construction shown in Fig. 16 to illustrate the special features of the highway member.

Figure 18 is a sectional half-view illustrating a simplified form of highway member which merely may be bolted directly to the flanged car wheel.

Figure 19 is a fragmentary face view of the highway member shown in Fig. 18 showing the clamping flange or bearing element formed by a tongue punched out of the web portion of the highway member.

Figure 20 is a detail elevational view showing a modification that may be resorted to in the construction shown in Fig. 19 to provide a positive lock against relative rotation of the car wheel and the highway member.

Figure 20^a is a detail sectional view of the suggested form of construction shown in Fig. 20, on the line 20^a—20^a of that figure.

Figure 21 is a sectional half-view showing a modified form of highway member shaped to provide clamping or bearing elements which respectively engage the car wheel and a holding nut or equivalent device.

Figure 22 is a sectional half-view showing another modification in the form of the highway member of the hub type.

Figures 23, 24, 25 and 26 are similar sectional half-views showing further modifications in the construction of the highway member adapted for use with a quick-detachable holding device.

Figures 27 and 29 are sectional half-views illustrative of a modification of the invention wherein a channel section is used to form the highway member, said views also illustrating other kinds of holding devices for securing the highway member in place.

Figures 28 and 30 are fragmentary elevations showing the methods used in Figures 27 and 29 for securing the highway member in place.

Figure 27^a is a detail view of a form of latch device that may be used as a holding means.

In carrying out the invention it is preferable to adapt it to the design and contour of a standard railway car wheel designated generally by the reference letter C. This car wheel includes the rim portion 1 formed with the usual coned tread 2 and the flange 3; and it is proposed, according to the present invention, to adapt to such a car wheel an attachment which will convert it for use on highways and streets. That attachment consists primarily of a highway member designated generally by the reference letter H and intended to be susceptible of a wide range of modification so long as the essential requirements thereof are preserved.

Among the essential requirements which are intended to be maintained and preserved,

in the present invention, is the primary one of so mounting the highway member with reference to the car wheel that it will wholly clear all portions of the car wheel tread and its flange which are subject to wear, and will have engagement and contact only on a part or portion of the wheel unaltered by wear or by machining to restore its contour. In the embodiment shown in Figure 1 of the drawings, the said highway member H includes a preferably thickened peripheral portion 4 constituting a tire which usually and preferably has a flat tread 5 adapting it for travel upon highways and streets.

Though the tire or tire element 4, may, as shown in Figure 1, overlie the tread 2 of the car wheel, the important feature here involved is that the tire element shall be entirely free from and out of contact with the normal contour of the tread and the flange, and, therefore, to be entirely independent, in its functioning, of any wear that may take place in the car wheel tread and the car wheel flange even to the extreme condemning limit shown by the full lines in Figure 1 of the drawings.

The tire element 4 of the highway member is carried by a web portion 6 which, in the form shown in Figure 1, may be arched or curved about the outer rim portion of the car wheel, and is formed with a clamping flange or element 7 which takes a bearing as at 8 against the under outer side of the rim member of the car wheel. Any suitable fastening or holding means may be utilized to hold the highway member H in its operative position and in Figure 1 is illustrated a construction for that purpose. Such construction includes an inwardly extending holding member or flange 9 which may be engaged by a fastening plate or equivalent member 10 fitted over an outer threaded spindle 11 at the outer side of the wheel axle, the said outer threaded spindle 11 being adapted to receive thereon a securing nut 12 which may or may not be provided with a nut lock or holding means, such as the cotter pin 11^a shown.

Substantially the same construction of highway member is shown in Figure 2 of the drawings, but in that figure of the drawings is given an illustration of a special form of locking device 13 which may be employed in connection with the fastening plate 10. As here shown this locking device consists of a nut 14 having interrupted or mutilated interior threads 15 cooperating with a hub spindle 16 having interrupted or mutilated threads 17. Such construction permits the locking device 13 to be quickly slipped over the alternately threaded spindle to an engagement with the fastening plate 10 and then rotated into locking engagement with the threads 17, the same being held in locked position by spring catches or equiv-

alent devices 18 engaging keepers or holes 19 in the fastening plate.

Figures 3, 4 and 5 are intended to illustrate changes in the form of the highway member, Figure 3 showing a member in which the clamping element or flange 7^a is pressed inwardly from the body of the web 6, and in Figure 4 the web of the highway member is shown having bearing engagement 10 with the under outer corner of the car wheel rim as at a, and from that point the web is continued down into the holding element or flange 9 for engagement by the fastening plate 10 or equivalent device. In Figure 5 15 the web of the highway member is shown continued down into a combined holding and clamping flange 9^a which has a bearing engagement as at 20 with the web of the car wheel, and, at 21, with the beveled 20 clamping edge 22 of a fastening plate 23 which may be conveniently held in place by a nut 24. The design shown in Figure 5 provides for a complete clearance for the 25 highway member from every part of the car wheel rim.

In Figure 6 of the drawings is shown a simplified construction wherein the highway member merely is provided with the web 6^b deflected as at X to form a ring-flange held 30 clamped against the beveled outer underside of the car wheel rim by a clamping plate 10^a, which clamping plate is held in place by a nut 25 on the threaded spindle 26 extending outwardly from the hub of the car 35 wheel. This form of the invention also shows complete clearance of the tire or tire element from all portions of the car wheel rim subject to wear or to machining to restore to contour.

40 The modification illustrated in Figure 7 of the drawings shows the highway member in the form of a complete wheel. That is, a member in which the rim 4^a with its flat tread 5^a is carried by a web portion 6^b which 45 has formed therewith a central hub part 27, preferably having a tapered inner bore 28 fitting over a correspondingly tapered nose 29 at the outer side of the car wheel hub and held in place by suitable locking nuts 50 30, as shown. Also, there is suggested in this form of construction a lock bolt 31 extending through the web of the highway member and engaging the car wheel and serving to prevent independent relative 55 movement of the two wheel parts. That detail may or may not be used without affecting the invention.

The form of construction suggested in Figure 8 of the drawings is similar to that 60 illustrated in Figure 7, that is, the highway member is in the form of a complete wheel whose web portion 6^b is provided with a central hub element or part 27^a, the latter in the present instance being interiorly 65 threaded, as at 31, for engagement with the

threaded spindle 32 formed at the outer side of the car wheel hub. In this form of construction the highway member is screwed on and off of the threaded spindle 32 of the car wheel hub and in its operative position 70 with relation to the car wheel may be held in such position by any suitable fastening or securing means such as the washer 33 and the cotter pin 34.

Another variation of the invention that 75 may be resorted to is shown in Figs. 9 and 10 of the drawings wherein the flanged car wheel may be mounted for free rotation upon a supporting journal or gudgeon 35 carried by the frame or axle part 36 of the vehicle. Such mounting of the flanged car wheel may either be directly on the supporting journal or gudgeon as shown in Figure 10 or with roller or equivalent anti-friction bearings 37 interposed between the bore of 80 the car wheel and the said journal or gudgeon as shown in Figure 9. However, in either forms of construction shown in Figures 9 and 10 the highway member may 85 be substantially similar to the highway member shown in Fig. 8 with its web 6^b provided with a threaded hub part 27^a engaging the threads of the threaded spindle 32 projecting outward from the hub of the car wheel. Also there is shown in the modifications of 90 Figures 9 and 10 an ordinary nut and washer 38 and 39 on the threaded tip 32^a for holding the car wheel upon its supporting journal or gudgeon, and a hub cap 40 provided with a threaded flange 41 engaging 95 the threads of the spindle 32 at the outer side of the hub of the highway member, thereby providing a holding means for securing the highway member in its operative 100 position and also serving as a cover for the nut and washer device which holds the car wheel on its journal.

A simplification of the form of construction shown in Figures 9 and 10 is illustrated in Figure 11 of the drawings, in which the flanged car wheel is shown provided at its outer side with a cylindrical supporting journal or gudgeon 42 having a threaded tip 43, thus admitting of the use of the highway member provided with a bearing hub 110 44 rotatably mounted on the supporting journal or gudgeon 42 of the car wheel and preferably having a lubricating passage 45 closed by a plug 46 or equivalent device. A nut or equivalent holding member 47 on the 115 threaded tip 43 provides a holding means for retaining the highway member on its 120 supporting journal or gudgeon.

The holding device shown in Figures 12 and 13 of the drawings obviates the use of 125 threaded members of all kinds and provides a quick detachable construction which admits of the highway member being readily brought into use or removed. This holding device is of the wedge type. Essentially it 130

consists of a rotatable stem 48 mounted to turn in a bearing hole 49 formed in the hub of the car wheel and carrying at its inner end a wedging head 50, one face of which head is beveled or inclined as at 51 to operate against a correspondingly beveled or inclined abutment face 52 formed at the bottom of a seat or socket 53 formed in the inner side of the car wheel hub. The outer end of the rotatable stem 48 may conveniently be squared or of angular formation as at 54 to removably receive thereover the perforated heel or end 55 of an operating lever 56 and detachably held in place by a pin or key 57, as shown. In the adaptation of the invention shown in Figure 12 of the drawings, the wedging holding device just described cooperates with a clamping plate 58 having an inturned holding edge or flange 59 that clamps upon an angular clamping foot 60 which is held by the plate 58 clamped upon an inclined or angularly disposed abutment shoulder 61 formed on and at the outer side of the car wheel. The said angular clamping foot 60 is formed at the inner edge of the web 61 of a highway member which otherwise has the other features of the invention hereinbefore described.

In the adaptation of the wedging holding device to the form of construction shown in Figure 13 of the drawings it will be seen by reference to that figure of the drawings that the highway member is formed with a web 62 deflected at an intermediate point to provide an inclined bearing element 63 engaging a correspondingly inclined clamping face 64 of the web of the car wheel; the said highway member web 62 being formed at its inner edge with a clamping flange 65 against which may directly bear the washer 66 with which the heel or end 55 of the operating lever 56 directly engages. In both forms of construction described, that is, the forms illustrated in Figures 12 and 13 of the drawings, it will be seen that by grasping the lever or handle 56 and rotating the stem 48 the wedging action of the head 50 against the seat or abutment 52 will serve to tightly and rigidly clamp the parts so as to hold the highway member in its operative position; and in the form of the invention shown in Figure 13 of the drawings, the highway member is shown as provided with a clincher rim or equivalent form of construction 67 adapted to carry a pneumatic or cushion tire 68. Also, it will be noted by reference to the dotted lines in Figure 12 of the drawings that these dotted lines may represent the axle part 69 of the vehicle to which the flanged car wheel is separately fastened by means of pins or equivalent elements 70.

The invention lends itself to various kinds of tires for the highway member, such for instance, those illustrated in Figures 1 to 13

of the drawings, but as shown in Figures 14 and 15 of the drawings the highway member may be adapted for carrying either a single solid cushion tire or a double solid cushion tire. The single solid cushion tire 71 is shown in Figure 14 of the drawings, the same being fitted to a specially constructed rim part 72 for the highway member H, which member also includes a bent or deflected web 73 provided with an inclined clamping shoulder 74 to engage the outer under side of the car wheel rim and a clamping flange 75 engaged by a unit 76 mounted on the threaded spindle 77 projecting from the hub of the car wheel. Or, as shown in Figure 15 of the drawings the highway member may be constructed with a special rim part 78 for carrying a double solid cushion tire 79; said highway member being further provided with a substantial or sturdy web 80 having at an intermediate portion thereof a reinforced clamping head or shoulder 81 engaging the outer underside of the rim of the car wheel. In this form of construction the web 80 of the highway member is shown provided with an interiorly threaded hub part 82 for engaging the exteriorly threaded spindle 72 of the car wheel hub.

The example of the invention shown in Figures 16 and 17 of the drawings includes a highway member provided with a web 83 from which is punched or struck out a laterally deflected bearing gusset 84 whose inclined side has a bearing or clamping engagement as at 85 with an inclined bearing face at the outer side of the car wheel and the inner edge of the said web 83 of the highway member may be provided with serrations or locking teeth 86 to be engaged by a locking dog 87 carried by a holding nut 88 which may be conveniently operated by a handle 89 and which is provided with a threaded part 90 engaging the threaded spindle 91 of the flanged car wheel.

A variation of the construction shown in Figures 16 and 17 of the drawings is suggested in Figures 18 and 19 of the drawings, wherein the highway member is shown provided with a comparatively short web or petticoat 92 having punched out therefrom a clamping tongue 93 engaging a built-up shoulder 94 on the car wheel at the underside of its rim. In this form of construction simple fastening bolts 95 may be used, said bolts extending through aligned openings in the web of the car wheel and the web of the highway member.

To illustrate the modification that may be resorted to in connection with the form of construction shown in Figures 18 and 19 there is shown in Figures 20 and 20^a the expedient of bending out of the web or petticoat of the highway member a clamping tongue or lip 96 curved or flanged so as to engage over and interlock with a rib or equiv-

alent projection 97 on the car wheel web, thereby providing a construction which locks the car wheel and the highway member against relative rotation.

5 Figures 21 and 22 of the drawings show simplifications of the invention, reducing the same to a minimum number of parts. In Figure 21 is shown a highway member of substantially S-shape in cross-section, the 10 outer part of said member being formed with a rim flange 98 overlying the tread of the car wheel and the web of said highway member is formed with a relatively long inclined clamping portion 99 having a flat clamping 15 engagement with a correspondingly inclined and extensive face 100 formed on the outer side of the car wheel web; the inner or hub part 101 of the said highway member web being curved outwardly to provide a holding 20 flange engaged by a nut or equivalent holding or securing element 102 suitably mounted on the hub of the car wheel. In Figure 22 the simple form of the invention shown consists of a highway member substantially 25 of a T-shape in cross-section and having its web 103 formed with a threaded hub element 104 engaging the threaded spindle 105 projecting from the hub of the car wheel flange. This form of the invention, namely, the one shown in Figure 22 of the drawings also includes the feature of the web 103 of the highway member having punched out therefrom at suitable points a gusset 106 similar to that shown in Figures 30 35 16 and 17 and which presents an inclined clamping portion for engagement with a correspondingly inclined face 107 at the outer side of the car wheel flange.

40 The group of Figures 23, 24, 25 and 26 are intended to illustrate the application of a quick detachable holding device to various forms of the highway member. Referring first to Figure 23 of the drawings it is seen that this quick detachable holding device primarily consists of a threaded spindle 108 at the outer side of the car wheel having steep pitch threads 109 adapted to be engaged by a correspondingly steep-pitched thread 110 carried by a holding collar 111 which is adapted to be quickly rotated onto and off of the spindle 108 by means of a handle 112. When screwed home the holding collar is held by a jam nut 113 having a steep-pitch thread 114 and which may conveniently be in the form of a hub cap. In its adaptation shown in Figure 23 of the drawings the quick detachable holding collar 111 is adapted to bind against the inner edge or flange part of the web 115 of the highway member which is constructed at its rim with clincher elements or equivalent devices 116 for carrying a cushion or equivalent tire 117. To provide the proper bearing or clamping engagement between this highway member and the car wheel the said

highway member may have pressed out from its web at suitable locations the clamping gusset 118, the inclined end of which gusset at 119 engages beneath the car wheel rim at the outer side thereof. Substantially the 70 same form of construction shown in Figure 23 is illustrated in Figure 24 adapted for use in connection with a single cushion tire 117a instead of the double cushion tire shown in Figure 23. 75

In Figure 25 of the drawings there is shown a modification of the quick detachable holding device of Figures 23 and 24 wherein the jam nut designated by the reference number 120 is shown provided with a handle 121 80 and a latch 122 which engages a keeper 123 in the holding collar 111 so as to prevent relative rotation of the holding collar and its jam nut. In said figure of the drawings there is also shown the feature of the web 85 124 of the highway member having pressed out therefrom nearly its full depth, from its inner edge to the rim part thereof, a relatively long clamping gusset 25 whose inclined face engages a correspondingly inclined face 126 at the outer side of the car wheel. The modification shown in Figure 26 is substantially that shown in Figure 25 excepting that the jam nut is not provided with the latch referred to and the web 127 90 of the highway member has punched out from an intermediate part thereof, at suitable locations, clamping gussets 128 for engagement with an inclined bearing face 129 at the outer side of the car wheel. 95

The group of Figures 27, 28, 29 and 30 are illustrative of an embodiment of the invention involving a rigid construction of highway member which can be readily manufactured or developed from a light 100 rolled or spun channeled disk or which can be pressed from light weight sheet steel, while the engaging bearings with the car wheel are rigid, well spaced, and well adapted for carrying and transferring the load. That is to say, in the embodiments of the invention shown in the group of figures referred to, the highway member H is shown formed of a channel section with its outer flange 130 providing the wheel tread 5, and the inner flange or web 131 thereof being provided or formed with a hub member 132 arranged over the hub extension 133 of the car wheel C. Also the web or flange 131 of the channel type highway member H is shown as being formed with a circular series of radially extending bearing tongues 134 which are of substantially triangular formation, and are formed by the slitting of the web of the highway member and pressing or deflecting the tongue 134 away from the channeled side of the highway member by turning them around an approximately radial axis, thereby forming inclined engaging portions to make contact with the 115 120 125 130

car wheel. In the form shown in Figures 27 and 28 of the drawings the inclined engaging portion 135 is formed along the side or side edge of the tongue, while in the 5 form shown in Figures 29 and 30 the bearing tongues 134 are merely reversed from the positions occupied by such tongues in Figures 27 and 28 of the drawings, thus bringing the inclined engaging portion 135^a 10 at the ends of these tongues. Therefore, in the construction shown in Figures 27 and 28 the inclined engaging portions 135 of the bearing tongues engage and abut an inclined part of the web of the car wheel, 15 while in the construction shown in Figures 29 and 30 the inclined engaging end portions 135^a have a bearing engagement against the under side of the rim of the car wheel.

20 In both forms of the invention shown in Figures 27-28 and Figures 29-30 the flanges 130, affording the tread for the highway wheel, do not overlie the car wheel tread but are turned in a direction away 25 from the car wheel. This feature of construction is of practical importance because it increases the width between the treads of the pair of highway wheels over the width between the pair of car wheels, thus providing 30 a greater resistance to rocking of the load while travelling over uneven or irregular highway surfaces.

The holding means for the highway member shown in Figure 27 of the drawings may 35 consist of a latch pin 136 provided with a suitable handle 137 and adapted to be held by a spring 138 in engagement with keeper holes 139 formed in the car wheel hub extension 133 between the coarse threads of 40 such extension, as clearly shown in the drawings. This form of latch device may also be provided, if desired, with a roller 140 for engagement with the sides of the threads of the hub extension as shown in Figure 45 27^a of the drawings. In this form of construction, the latch with or without the roller, can be lifted entirely free from the threads of the hub of the car wheel extension so that the highway attachment can be 50 pulled straight off or pushed straight on, instead of requiring several complete revolutions as would be necessary with fully engaged threads. When the highway attachment is turned "home", that is against 55 the car wheel, the latch is then allowed to drop between the threads, and the attachment is revolved into a tightly binding position until the latch pin drops into the nearest keeper hole 139, thus holding the two wheels 60 tightly together until the latch is again released in order to remove the highway wheel.

In the modification shown in Figures 29 and 30 of the drawings the same coarsely 65 threaded hollow car wheel hub extension is

shown, and the holding device may consist merely of a set screw 141 which may be easily tightened or loosened according as the highway wheel is to be locked in place or freed, and the hub 132 of the highway member 70 may have fitted thereto a fixed stud 142 for engagement with the coarse threads of the car wheel hub extension. The stud and set screw referred to may be used either independently or in combination, or in any desired number without affecting the invention. 75

The illustrations herein referred to are believed clearly to exemplify the particular 80 phases of the invention claimed herein, and it is therefore thought that the essentials of the invention will now be understood without further description, and also that changes in the form, proportion and minor 85 details of construction may be resorted to without departing from the spirit or sacrificing any of the advantages of the invention.

I claim:—

1. A convertible wheel structure including 90 a flanged railway car wheel having an outer rim portion projecting beyond the outermost face of its web or spoke portion, and a highway attachment comprising a tread member adapted to have clearance from all tread 95 portions of the wheel.

2. A convertible wheel structure including flanged railway car wheel and a highway attachment comprising a tread member adapted to be clampingly engaged with the 100 car wheel and having clearance from all portions of its flange and hub.

3. A convertible wheel structure including a flanged railway car wheel, and a highway 105 attachment comprising a tread member adapted to be clampingly engaged with the car wheel and having clearance from the normal unworn tread and flange thereof, said structure providing a free space between the highway member and a portion 110 of the upright outer face of the wheel rim.

4. A convertible wheel structure including a flanged railway car wheel having an outer rim portion projecting beyond the outermost 115 face of its web or spoke portion, a highway attachment comprising a tread member having clearance from the wheel flange, and releasable holding means for said member.

5. A convertible wheel structure including a flanged railway car wheel, a highway 120 attachment comprising a tread member adapted to be held entirely free from contact with any part of the car wheel subjected to wear, said structure providing a laterally variable free space between the highway member in its tightened position and the wheel rim to allow for wear and tolerances, and means for holding the highway member 125 releasably clamped to the car wheel.

6. A convertible wheel structure includ- 130

- ing a flanged railway car wheel, a highway member lying entirely free of contact with any part of the car wheel subjected to wear, and means for holding the highway member 5 releasably clamped to the underside of the rim of the car wheel.
7. A convertible wheel structure including a flanged railway car wheel, a highway member lying entirely free of contact with any part of the car wheel subjected to wear, and means for holding the highway member 10 releasably clamped to the underside of the outer portion of the rim of the car wheel.
8. A convertible wheel structure including a flanged railway car wheel, a highway member adapted to be clamped to the car wheel, free of its wearing surfaces and having a rim overlying the tread of the car wheel and a web provided with a holding 15 member, and a fastening device supported from the car wheel and adapted to engage said holding member.
9. A convertible wheel structure including a flanged car wheel, a highway member 20 having a rim adapted to overlie the tread of the car wheel and standing free thereof and of the flange, and fastening means for clampingly engaging the highway member with the rim part of the car wheel.
10. A convertible wheel structure including a flanged railway car wheel, a one-piece 25 highway member standing entirely free from the wheel hub, and centrally located means for clamping the same to the car wheel.
11. A convertible wheel structure including a flanged railway car wheel, a one-piece 30 highway member standing entirely free from the wheel hub, and centrally located means for releasably clamping the same to the car wheel.
12. A convertible wheel structure including a flanged railway car wheel, a one-piece 35 highway member adapted to provide a free space between said member and a portion of the upright outer face of wheel rim and centrally located means for detachably clamping the highway member to the car wheel.
13. A convertible wheel structure including a flanged railway car wheel, a highway member adapted to stand entirely free of contact with the tread, flange and hub of the wheel, and means for detachably clamping 40 said member to the car wheel.
14. A convertible wheel structure including a flanged railway car wheel, a highway member adapted to provide a free space between said member and a portion of the upright outer face of wheel rim, and adapted 45 to have a clamping engagement on a portion of the car wheel unaltered by wear or by machining to restore contour.
15. A convertible wheel structure includ- 50
- ing a flanged railway car wheel and a highway member adapted to be detachably held to the car wheel and standing entirely free from contact with the wheel flange and also providing an interposed free space between itself and the greater portion of the outer 55 face of the wheel rim.
16. A convertible wheel structure including a flanged railway car wheel and a highway member adapted to be detachably held to the car wheel and standing entirely free 60 from contact with any part of its flange, and also being free from load carrying or bearing surfaces on the wheel hub.
17. A convertible wheel structure including a railway car wheel, a highway attachment, and a locking device comprising an offset or positive stop portion and corresponding interlocking part for limiting relative rotation of said car wheel and said attachment, said locking device lying toward the wheel center and entirely within a cylindrical surface intersecting the middle of the wheel rim and co-axial with the wheel.
18. A convertible wheel structure including a railway car wheel, a highway attachment comprising a tread member, and a locking device consisting of an offset or positive stop portion and an interlocking part 65 acting to limit relative rotation between the car wheel and said tread member, said locking device lying toward the wheel center and entirely within a cylindrical surface intersecting the middle of the wheel rim and co-axial with the wheel.
19. A convertible wheel structure including a railway car wheel, and a highway attachment comprising a tread member adapted to be drawn into a tightened position against a conical face lying within the circle defined by the outermost edge or portion of 70 the outer face of the wheel rim.
20. A convertible wheel structure including a flanged railway car wheel, and a highway member extending from a point adjacent to the wheel hub to a point adjacent to 75 the wheel rim, and standing entirely free from the wheel hub and wheel flange.
21. A convertible wheel structure including a flanged member for tracks and a member for highways, and rotary clamping 80 means co-axial with said members.
22. A convertible wheel structure including a flanged tire member for tracks and a tread for highways, and a clamping member adapted to revolve co-axially with at 85 least one of said other members.
23. A convertible wheel structure including a flanged member for tracks and a member for highways, one of said members having a portion threaded co-axially with its 90 axis of rotation.
24. A convertible wheel structure includ- 95
- ing one member adapted to run on tracks

- and another member adapted to highways, and rotary clamping means co-axial with at least one of said members.
25. A convertible wheel structure including a flanged member for tracks and a member adapted to highways, and a quick-action rotary clamping and release member engaging at least one of said other members.
26. A convertible wheel structure including a flanged member for tracks and a member adapted to highways, and clamping means engaging a portion of one of said members threaded co-axially with its own axis of rotation.
- 10 27. A convertible wheel structure including a flanged member for tracks and a member adapted to highways, and means adapted to clamp together and to release said members by rotary movement of one part.
- 15 28. A convertible wheel structure including a flanged member for tracks and a member adapted to highways, and a quick-action releasable clamping member revolving co-axially with at least one of said other members.
- 20 29. A convertible wheel structure including a flanged member for tracks and a member adapted to highways and a member to hold the parts together, one of said members revolving co-axially with the track or the highway member into a tightened position.
- 30 30. A convertible wheel structure including a flanged member for tracks and a member adapted to highways, and clamping means comprising threaded or revolving-wedge members adapted to turn co-axially with at least one of said other members.
- 35 31. A convertible wheel structure including a highway appliance releasably engaging a flanged car wheel for tracks, one member of said appliance revolving co-axially with said car wheel into a tightened operative position.
- 40 32. A convertible wheel structure including a flanged member for tracks and a member adapted to highways, and a releasable clamping member, one of said members turning concentric with said track member into a tightened operative position around a threaded portion or against a face lying at an angle to the plane of the outer face of said track member.
- 45 33. A convertible wheel structure including a railway car wheel, a highway attachment, and clamping means to hold the highway attachment in operative position, said clamping means comprising two or more separately moving members and a lock to limit the relative movement of these mem-
- bers, at least a portion of said lock to extend within a cylindrical surface defined by the under face of the wheel rim.
- 50 34. A convertible wheel structure including a flanged railway car wheel and a highway attachment having a tread member, more than one-half of the tread of said member lying outside of the plane of the normal vertical outer face of the wheel rim.
- 55 35. A convertible wheel structure including a flanged railway car wheel and a highway attachment having a tread member, more than one-half of the tread of said member lying outside of a vertical plane parallel to the plane of the car wheel at the outer edge of its tread.
- 60 36. A convertible wheel structure including a flanged railway car wheel and a highway attachment having a tread member, more than one-half of the tread of said member lying horizontally beyond the normal tread width of the car wheel.
- 65 37. A convertible wheel structure including a flanged railway car wheel, and a highway attachment including a tread member and a clamping member, one of said members being adapted to be revolved around the axis of the wheel into a tightened position.
- 70 38. A convertible wheel structure including a flanged railway car wheel, and a highway attachment having at least two members, one of said members being so constructed that when revolved around the axis of the wheel it is drawn into a tightened position by a thread or by a plane lying at an angle to the outer wheel face.
- 75 39. A convertible wheel structure including a flanged railway car wheel, and a highway appliance having a clamping and releasing member concentric with the wheel hub and adjacent to it.
- 80 40. A convertible wheel structure including a flanged railway car wheel having a threaded portion projecting from its outer face beyond the normal width of the wheel rim, and a highway appliance engaging said threaded portions, said appliance including tread member and releasable clamping means.
- 85 41. In a convertible wheel structure, a flanged car wheel, a highway member engaging the rim part of the flanged car wheel and free from contact with the wheel flange, and a quick release catch or fastening to lock or limit the movement of the highway member against release from its tightened operative position.
- 90 In testimony whereof I hereunto affix my signature.
- SAMUEL GARVER THOMSON.
